UNITED STATES PATENT OFFICE.

JOHN S. CUTHBERTSON, OF MONTREAL, QUEBEC, CANADA.

CLOSURE FOR RECEPTACLES.

Application filed May 23, 1922. Serial No. 563,098.

To all whom it may concern:

Be it known that I, JOHN S. CUTHBERTSON, a subject of the King of Great Britain, and resident of the city of Montreal, in the 5 Province of Quebec and Dominion of Canada, have invented certain new and useful Improvements in Closures for Receptacles, of which the following is a full, clear, and exact description.

10 This invention relates to closures or stoppers for receptacles, the main object of the invention being to provide a simple, inexpensive and efficient means of closing and sealing the orifice of a hot water bottle or 15 the like.

The invention consists essentially in providing a metal tube or sleeve adapted to fit into the neck of a hot water bottle, and a fabric covered rubber stopper fitting into 20 the tube, and provided with means whereby the stopper may be expanded to seal the tube or may be contracted to withdraw the stopper from the tube as desired.

In the drawings which illustrate my invention:—

Figure 1 is a vertical sectional view of the stopper fitted into a bottle neck.

Figure 2 is a vertical elevation of the same.

30 Figure 3 is a plan view.

Referring to the drawings, 10 designates a hot water bottle or the like, usually made of rubber, and into the neck of this bottle is fitted a metal tube or sleeve 11. The 35 sleeve is bell mouthed at the bottom as indicated at 11^a, and the rubber neck of the bottle is drawn over the sleeve and sealed by any suitable means. The sleeve 11 is provided at the top with a flange 12 of larger 40 diameter than the bottle neck, and the upper surface of the flange is provided with a projecting pin or boss 13. The stopper which is adapted to co-act with the metal sleeve 11 is made as follows:—A lower compression 45 member comprising a circular flange 16 and carrying a threaded spindle 17 co-operates with an upper compression member or washer 14, apertured to receive the threaded spindle 17. Between the plates 14 and 16

50 I provide an elastic stopper 20 of rubber or the like. This stopper is apertured longitudinally as indicated at 21 to fit over the spindle 17. The rubber stopper is also provided with an exterior covering 22 of fabric, 55 to prevent deterioration or vulcanizing of the rubber by excessive heat. The lower

compression member 16 is slightly smaller in diameter than the diameter of the stopper, and the upper compression member 14 is provided with a circumferential slot 15 60 adapted to co-operate with the projection 13 on the upper surface of the flange 12. A threaded nut 18 of ring form or any other suitable shape is threaded on to the upper end of the spindle 17, the lower face 19 of 65 the nut fitting down upon the upper surface of the washer 14. When the nut is screwed on to the spindle the upper end of the latter may be slightly enlarged to prevent the nut from coming off.

70 When the stopper is inserted into the sleeve and the plate 14 is forced down on the flange 12, the circumferential slot 15 is fitted over the projecting pin 13. By turning the nut the plates 14 and 16 are forced together 75 and the stopper is prevented from turning in the sleeve by means of the projection 13 acting against the edges of the plate 14 in the slot 15. As the stopper is prevented from turning within the sleeve the plates 14 80 and 16 may be drawn together, thus expanding the rubber stopper within the neck 11 and thereby tightly sealing the orifice. To release the stopper, the nut is turned in the opposite direction, the plate 14 rotating 85 until the opposite edge of the slot 15 is forced against the projection 13. As the plates 14 and 16 recede from each other the stopper is contracted circumferentially and may be easily withdrawn from the neck of 90 the bottle.

Having thus described my invention, what I claim is:—

1. A closure for bottles comprising a flanged sleeve adapted to be fitted within the neck of a bottle, and a stopper comprising an upper compression plate resting on the flange of said sleeve, interengaging means carried by the flange and plate for holding the latter against turning movement, a lower compression plate, a rubber closure member mounted between said plates, and means for moving said plates toward or away from each other to circumferentially expand or contract the rubber closure member.

2. A closure for bottles comprising a flanged sleeve adapted to be fitted into the neck of a bottle, a projection on the flange of said sleeve, and a compression plate having a slot adapted to fit over said projection, a second compression plate having a threaded spindle extending through an aperture in

the first compression plate, a rubber stopper mounted on said spindle, and means for moving said plates toward or away from each other to circumferentially expand or contract the rubber stopper.

3. In combination, a bottle composed wholly of elastic material, such as rubber, a metallic sleeve fitted in the neck of said bottle and having its upper and lower ends turned outwardly, the outwardly turned portion at the upper end of the sleeve being formed to provide a relatively wide and horizontally disposed flange overlying the upper edge of the bottle neck and a stopper comprising an elastic element expansible into frictional gripping engagement with the inner wall of said sleeve, upper and lower compression plates engaging the top and bottom portions of said elastic element, said upper plate be-

ing of sufficient diameter to rest upon the 20 aforementioned flange and being provided with a slot adapted to receive a projection on the flange and means for moving said compression plates relatively to one another including a threaded stem carried by the 25 bottom plate and projecting upwardly through the top plate and a nut threaded on said stem.

4. In combination, a bottle composed wholly of elastic material, a metallic lining 30 sleeve inserted in and serving to reinforce the neck of said bottle and a stopper capable of expansion and contraction to engage and disengage the inner wall of said sleeve.

In witness whereof, I have hereunto set 35 my hand.

JOHN S. CUTHBERTSON.
